FOOT MASSAGING DEVICE

James A. Brogan, Lawrence, Mass.

Application December 1, 1934, Serial No. 755,605

3 Claims. (CL 128—57)

The present invention relates to foot massaging devices and more particularly to that type thereof in which a massaging roll is rotated in engagement with the plantar surface of the foot.

It has been proposed heretofore to provide foot massaging devices of the roll type, the various devices comprising single rolls or a series of rolls associated together for this purpose. In one type the roll is supported only by the floor, and moves along it. In other types the roll is supported so as to have a fixed axis of rotation. But whatever these types may be, they have lacked certain features of construction by which the most beneficial massage results may be obtained. Many prior art devices, while moving along the longitudinal arch of the foot, act on the foot primarily in a transverse direction. Whether the devices have been provided with one roll or with several, attention has been directed upon the transverse kneading of the foot, and the longitudinal kneading has been disregarded. But this longitudinal kneading is actually a matter of greater importance in correcting foot ailments since the major movements of the foot, such as in walking and the flexing of the toes, are effected by, or cause, bone, muscle, and tendon movements in the direction of the length of the foot, and the reason is that the direction of articulation of the bones of the foot is largely longitudinal.

Accordingly, it is the principal object of the present invention to provide a foot massaging device in the use of which the plantar surface of the foot is kneaded and massaged in the direction of the length of the foot. To the accomplishment of this object, a feature of the present invention contemplates the provision, in a foot massaging device, of a roll provided circumferentially with longitudinal flutes.

A further construction found in prior art devices is the feature that the axis of rotation and the longitudinal center line of the roll or rolls coincide. Stated in another way, in these devices the uppermost point of the lateral surface of the roll, whether the axis of rotation be fixed or floating, is always the same distance from the floor or support. By reason of this construction the plantar surface of the foot engages a rolling surface that has a constant level, and as a result, with a given amount of pressure, the heavy bones of the tarsal region of the foot, which should receive increased pressure, receive no more pressure than is received by the metatarsal and phalanges regions.

It is therefore a further object of the present invention to provide a foot massaging device adapt-

ed to subject the heavy bones of the tarsal region of the foot to a greater massaging pressure than the metatarsal and phalanges bones. To the accomplishment of this object, a feature of the present invention contemplates the provision in a foot massaging device of a roll so mounted that the surface portion thereof which engages the foot has a level that constantly varies. Broadly considered, this object may be achieved by the provision of a plain roll mounted so that its axis of rotation is eccentric of its longitudinal center line. It is preferred, however, to combine this eccentric mounting with the longitudinal fluting so that simultaneously with the variance in pressure, the foot may be kneaded and massaged in the direction of the articulation of the bones.

A further construction found in prior art devices is the provision that the foot engaging surface of the roll is curved from one end of the roll to the other, the purpose being to provide an approximation to the curvature of the transverse arch of the foot. Desirable as such a construction is, it is apparent that a curved surface in a single roll does not provide for a contact point sufficiently narrow to press against the foot locally as compared to the general pressure exerted by the entire roll on the entire plantar surface of the foot.

It is therefore a further object of the present invention to provide a foot massaging device adapted to subject any particular part of the plantar surface of the foot to a greater pressure than that to which the remainder of the plantar surface is subjected. To the accomplishment of this object, a feature of the present invention contemplates the provision of a roll which is shaped like the frustums of two right circular cones the larger bases of which are merged. Broadly considered, such a roll might be plain and might also be mounted for rotation along its longitudinal center line. It is preferred, however, to combine this frusto-conical feature with the longitudinal fluting and/or with the eccentric mounting of the roll, as the benefits from the localized pressure obtainable with a frusto-conical roll are enhanced by the kneading action longitudinally of the foot and/or by the variance in the level of the foot engaging surface of the roll and the consequent variance in pressure resulting therefrom.

To the accomplishment of these objects and such others as may appear hereinafter, the various features of the present invention reside in certain devices, combinations, and arrangements of parts fully described hereinafter and then

pointed out in their true scope in the appended claims.

The illustrated embodiment of the present invention will be readily understood from an inspection of the accompanying drawing illustrating the best form of the invention at present known to the inventor, in which,

Figure 1 is a view in plan of the device;

Fig. 2 is a view in side elevation, partially in construction lines, illustrating the change of position of the roll when caused to rotate in engagement with the foot; and

Fig. 3 is a view in sectional elevation taken along the line 3—3 of Fig. 1.

Referring to the drawing, the illustrated embodiment of the present invention is provided with a flat base 5 from which are cut and upwardly bent two integral and oppositely disposed arms 6 and 7. The tops of the arms 6 and 7 are provided with slots 8 and 9, respectively, the bottoms of which are semi-circular to form journals for the projecting ends of aligned pins 10 and 11 partially embedded in the opposite ends of a roll 12. To insure that the ends of the roll 12 do not rub on the arms 6 and 7, the pins 10 and 11 are preferably provided adjacent their projecting ends with flanges 13 (Fig. 3) which abut the slotted ends of the arms. As shown in Figs. 1 and 3, the base 5 extends well beyond the ends 30 of the roll 12 to provide foot rest portions 14 and 15, on one of which, as the case may be, the user places the foot he is not exercising so as to hold the base firmly against a supporting surface such as a floor.

The roll 12 is preferably solid and has a varying diameter which is greatest at the longitudinal center of the roll and decreases in the direction of the opposite ends thereof. Stated in another way, the roll 12 illustrated is shaped like the frustum of two right circular cones the larger bases of which are merged. As a result of this merging, an apex or arris C is formed at the center of the roll, (Figs. 1 and 3). As indicated best in Fig. 2 the roll 12 is provided circumferentially 45 with longitudinal flutes 16 which are spaced so that fillets 17 are provided between successive flutes. As a matter of construction, the bases 18 of the flutes 16 may be more or less parallel with the fillets 17. As a practical matter, however, 50 when the roll is made by turning and cutting, as opposed to a molding operation, it is preferred that the bases of the flutes 16 be straight throughout their length. Such a construction results in the side walls 19 (Fig. 3) of the flutes 16 having a height that decreases in the direction of the 55 opposite ends of the roll.

Viewing Figs. 2 and 3, it will be seen that the aligned pins 10 and 11 do not project from the longitudinal center line of the roll 12, but are spaced therefrom. Stated in another way, the aligned pins 10 and 11 are eccentric of the roll, and thereby cause the rotation of the roll to be eccentric. This feature of construction has an important bearing on the foot massaging operation of the device, as will appear hereinafter.

By reason of the eccentric position of the pins 10 and 11, it will be seen that when the pins are journaled in the slots 8 and 9, the center of gravity of the roll, being spaced from the axis of rotation, causes, or tends to cause, the roll to assume in disuse the full line position shown in Fig. 2, i. e., a position in which the greater part of the roll is located beneath the axis of rotation formed by the pins 10 and 11. To facilitate this 75 assumption by the roll 12 of its full line Fig. 2

position, the opposite ends of the roll 12 may be provided with weights 20 and 21 which cause the center of gravity of the roll to be spaced still further from its axis of rotation.

In using the illustrated embodiment of the present invention, the device is positioned with the base 5 resting on the floor. By reason of the eccentric mounting of the roll 12, it will assume the position shown in full lines in Fig. 2. The user, if exercising his right foot, places his left foot on the foot rest portion 14 thereby holding the device firmly in place. The user first engages the fillets 17 with the forward portion of the sole of his foot, as indicated by the foot A, (Fig. 2), and then, exerting pressure on the roll, 15 moves his foot forward, i. e., to the right, viewing Fig. 2, to the position shown by the foot B. From this position the foot is moved back to the position shown by the foot A, and this foot reciprocation is continued as long as the user desires. 20

During this reciprocation of the foot pressed in engagement with the roll 12, it will be noticed that the eccentric mounting of the roll causes the height of the uppermost point on its lateral surface to constantly vary as the roll rotates. With 25 the foot in the position of the foot A, for example, the height of the uppermost point on the lateral surface of the roll is the least, as indicated in full lines. When the foot is in the position of the foot B, however, the height of the 30 uppermost point on the lateral surface of the roll is greatest, as indicated in construction lines, the difference between the two heights being the amount of spacing of the aligned pins 10 and 11 from the longitudinal center line of the roll. 35 Stated in another way, when the illustrated device is in use, the foot moves forward in contact with a rotating surface that is constantly rising, and moves backward in contact with a rotating surface that is constantly receding. The 40 foot rises and falls in its movement as the lateral surface of the roll rises and falls, but it will be seen that this rising occurs as the heavy bones of the tarsus region of the foot are approached by the roll and that this falling occurs as the 45 smaller bones of the metatarsus region are approached. The result of this movement is that the tarsal region of the foot presses harder on the roll than does the metatarsal region, and by reason of this greater pressure, the kneading action is greater at the tarsal region than at the 50 metatarsal region. At the same time the flutes 16 cause the plantar surface of the foot to be kneaded and massaged in the direction of the articulation of the bones of the foot, so that these 55 bones and the associated muscles and tendons are massaged and exercised in the direction in which they normally and chiefly move.

While the present device is designed primarily to knead and massage the longitudinal arch 60 region of the foot, the force of the kneading and massaging increasing as the heavy bones of the foot are approached, the roll 12 may also be utilized to treat the phalanges-metatarsal region of the foot. By reciprocating the toes and the 65 ball of the foot over the roll 12, the toes are clenched and unclenched and the flutes 16 simultaneously with this action knead the foot in the direction of the articulation of the small bones in the forepart of the foot and thus strengthen 70 the muscles and tendons in the ball region.

Several further features should be pointed out concerning the illustrated construction. The roll 12 is long enough so that when no special locality of the plantar surface of the right foot is to be 75

massaged, it may be caused to overlie chiefly the right hand frusto-conical portion, and so that when no particular locality of the plantar surface of the left foot is to be massaged, it may be caused to overlie chiefly the left hand frusto-conical portion. On the other hand, when a local area of the plantar surface of the foot should be particularly massaged, that area is placed over the apex C and the foot is then reciprocated as above described. The beneficial results derived from the provision of the apex C are enhanced by the kneading action of the flutes 16 and by the varying level of the foot engaging surface of the roll. It will be apparent however, that beneficial localized pressure will result without either or both of these last named features.

The flutes 16 are shown spaced to provide fillets 17 between successive pairs, but the flutes 16 may be so disposed as to provide an arris between successive pairs. The illustrated fillets are preferable, however, because the relatively sharp edges formed by arrises would provide too little surface to engage the foot, and the edges would tend to become uncomfortable. It should also be pointed out that the longitudinal flutes 16 would perform a beneficial kneading and massaging of the plantar region of the foot even if the roll 12 were not eccentrically mounted and if there were no apex C, the reason being that the flutes 16 would still cause a kneading and massaging action in the direction of the articulation of the bones of the foot. The kneading action of the flutes 16 combined with the rising and falling of the lateral surface of the roll and/or the apex C, however, produce a combined massaging action that is more beneficial. The base 5 and the arms 6 and 7 shown are merely one illustration of how the roll 12 may be mounted, and the advantage of this construction is its simplicity. It will be obvious that other forms of roll supports could be used with equal success.

What is claimed as new is:

1. In a foot massaging device, the combination with a support adapted to be maintained stationary upon a floor, of a roll journaled eccentrically upon said support for rotative movement under the influence of the pressure and movement of the user's foot, said roll being provided with longitudinal flutes extending from one end of the roll to the other and having fillets therebetween adapted to engage and knead the plantar surface of the foot, and said roll also being weighted between its axis of rotation and its foot engaging surface to facilitate the tendency of the roll, by reason of said eccentricity, to return to a given position in disuse. 5

2. A foot massaging device having, in combination, a support for a roll, an extension on at least one side of the support on which a user may stand with one foot to maintain the support stationary on a floor, and a longitudinally fluted roll mounted eccentrically on said support for rotation under the pressure and movement of the user's other foot, said roll being weighted between its axis of rotation and its foot engaging surface to facilitate the tendency of the roll, by 10 reason of said eccentricity, to return to a given position in disuse. 15

3. A foot massaging device having, in combination, a support for a roll, an extension on at least one side of the support on which a user 20 may stand with one foot to maintain the support stationary on a floor, and a longitudinally fluted roll mounted eccentrically on said support for rotation under the pressure and movement of the user's other foot, the foot engaging surface of 25 said roll comprising surface portions of two truncated cones the larger bases of which merge and said roll being weighted between its axis of rotation and its foot engaging surface to facilitate the tendency of the roll, by reason of said 30 eccentricity, to return to a given position in disuse. 35
